EXERCISING APPARATUS

Filed Feb. 7, 1929

INVENTOR

UNITED STATES PATENT OFFICE

FRANK L. DYER, OF NEW YORK, N. Y.

EXERCISING APPARATUS

Application filed February 7, 1929. Serial No. 338,097.

My invention relates to various new and useful improvements in exercising apparatus of the type in which an electric motor operates to move an endless belt with a vibratory motion and with sufficient power to cause a bodily movement of the user of the apparatus.

In an application for Letters Patent filed February 2, 1929, Serial No. 337,123, I describe an apparatus of this kind in which the mechanism is specifically shown as being carried upon a door preferably closing a closet so as to permit the apparatus to be disclosed for use upon opening said door and in that application I show a connection between the exercising mechanism and a stationary abutment independent of the hinges of the door whereby the strains and stresses incident to use will not be imposed upon said hinges. In this application I refer to a modified arrangement in which the exercising apparatus is supported independently of the door so that not only will the vibrating stresses due to operation be independent of the hinges but the weight of the apparatus also. It is the purpose of my present case to describe and specifically claim this modification.

In order that the invention may be better understood, attention is directed to the accompanying drawing forming part of this specification, and in which—

Figure 1 is a horizontal sectional view through a door and the jamb thereof showing a conventional form of exercising apparatus in plan; and

Figure 2 is a side elevation partly in section, showing one of the door jambs.

In both of the above views corresponding parts are represented by the same numerals.

The door 1 closes the opening between two door jambs 2, 2, and is supported on ordinary hinges 3. Said door preferably closes a closet so that when shut the apparatus will be concealed therein. A bracket 4 having an inclined brace member 5 is mounted upon one of the door jambs as shown, on heavy cast metal plates 6, 6 having horizontal ears 7, 7 receiving the pivot pins 8, 8 so as to form a very strong and rigid mounting for the frame 4, 5.

The bracket member 4 carries a base 9 upon which is mounted the base 10 of the exercising apparatus. Preferably anti-friction balls 11 are interposed between these elements so as to permit the exercising apparatus to move readily with respect to the base 9 in a horizontal plane. A heavy belt or strap 12 leads from an ear 13 depending from the base plate 10 and connects with a suitable bracket 14 secured to any fixed element, such as one of the door jambs 2 as shown. A spring 15 keeps the strap 12 normally taut.

The exercising apparatus shown, comprises an electric motor 16 driving a shaft 17 by which the plungers 18, 18 are operated. These plungers are connected by an endless belt 19 which is placed around the body of the user.

A heavy spring 20 preferably connects the door 1 with the base plate 9 so that when said door is opened the apparatus will be swung out into operative position. It may be held in this position by hook arm 21 secured to one of the door jambs and engaging a lug 22 on the base plate 9.

Having now described my invention, what I claim as new and desire to secure by Letters Patent, is as follows:—

1. In exercising apparatus, the combination with a doorway and a door adapted to close the same, of a hinged bracket pivoted within said doorway independent of the door, motor driven vibrating mechanism carried by said bracket and movable in a horizontal plane independently thereof, and a connection between said mechanism and a stationary abutment.

2. In exercising apparatus, the combination with a doorway and a door adapted to close the same, of a hinged bracket pivoted within said doorway independent of the door, motor driven vibrating mechanism carried by said bracket and movable in a horizontal plane independently thereof, a connection between said mechanism and a stationary abutment, and a spring for imposing tension on said connection.

FRANK L. DYER.
